COMBINED STAMP VENDING AND
ADVERTISING MACHINE

Clarence M. Wheeler, St. Louis, Mo.

Application October 12, 1934, Serial No. 748,074

3 Claims. (Cl. 40—32)

This invention relates to vending and advertising devices and more particularly to a combined advertising and postage stamp vending machine, having for its main object to produce a novel and attractive machine from which postage stamps may be delivered to the patron at face value, automatically, upon the insertion of a designated coin for a given number of the stamps selected.

- 10 The invention consists in the novel general arrangement of the mechanism or operating parts of the respective coin-controlled vending devices and means for displaying advertising matter attractively, whereby, revenue for the operation 5 and maintenance of the machine is obtained by the owner or lessee from the advertiser or advertisers and to the resultant benefit of the latter. The invention further consists in the parts and combinations and arrangements of the parts of 20 the respective mechanisms, and, more particularly, in the special adaptation of said mechanisms for inter-dependent and practical co-operative working combination, together with simplicity and economy in operation and maintenance.
- 25 Objects and advantages to be attained, and structural features, other than hereinabove set forth, will hereinafter more fully appear in the following description.

In the accompanying drawings forming part 30 of this specification and illustrating a practical embodiment of the invention,—

Figure 1 is a front elevation of a fanciful cabinet housing the mechanism;

Figure 2 is a side elevation thereof;

35 Figure 3 is a front elevation of the interior mechanical structure, with the cabinet removed;

Figure 4 is a side elevation of the right side of the interior structural assembly as shown in Figure 3;

40 Figure 5 is a side elevation, looking at the left side of the structure, with portions of the side plate removed to show interior structural arrangements;

Figure 6 is a similar view at the right side of 45 the structure, with the greater portion of the near side plate broken away to show a practical arrangement of the carrier rolls for the advertising endless-belt strip or film;

Figure 7 is a fragmentary detail view to show 50 the preferred manner of joining the respective separable panels or sheets of the advertising endless-belt strip or film;

Figure 8 is a view, on a greatly enlarged or 55 exaggerated scale, showing fragments of the meeting end portions of two panels or sheet ele-

ments of the advertising endless-belt strip or film detached, together with a fragment of the transverse connecting wire;

Figure 9 is a fragmentary side elevation of the right side plate in the region where the controlling and operating devices for the intermittently operated advertising endless-belt strip or film and the brake device for the strip or film are located; and

Figure 10 is a fragmentary detail view showing, 10 in a more or less conventional manner, means for intermittently breaking the electrical circuit for the light bulb which illuminates the advertising endless-belt strip or film.

Referring now to the drawings, the numeral 15 1 designates the cabinet or outer casing of the machine, which, as shown in the illustrative drawings, is of substantially square lower body portion, which is mounted on the fancifully designed base portion 2, the front upper portion being sloped, 20 as at 3. In the sloping portion 3 is a window or display opening 9 for the endless-belt advertising strip or film to be later more fully described, this window opening being obviously provided with a protective pane or panel of glass or other suitable transparent material. At the top of the cabinet 1, and located near the rear wall, is an upstanding head-piece 4 on which is displayed suitable reading matter to indicate that the machine vends postage stamps at face value, the 30 front face of this head-piece being preferably inclined, as shown.

Near the opposite right and left sides of the cabinet, the sloping portion 3 is provided with coin-receiving slots, the one, 5, as shown and indicated, being for practical purposes designated as for the reception of a dime (10¢) and the other, 6, for a nickel (5¢), it being, of course, understood that in either application five stamps will be automatically delivered from the machine, as will later be more fully described. In the lower front wall portion of the cabinet, in vertical correlation to the respective coin-receiving slots, are dispensing openings 7 and 8, respectively.

Referring now more particularly to Figures 3 45 and 4 of the drawings, the stamp vending mechanisms will be described, generally, as to their individual characteristic structures, and, more specifically, as to their co-operative relation to and operation in conjunction with the advertising 50 mechanism.

There are two of the stamp vending mechanisms, one, designated generally by the numeral 10, at the left side of the machine, and the other, designated by the numeral 11, at the right side, 55

as shown. These mechanisms may be of any approved structure, and suffice it to describe them generally as having provision for supporting as at 12, reels of stamps in continuous strips 13, 5 which may be perforated for easy detachment, or not, as preferred, because an automatically operated knife element 14 is provided for each vending unit, the strip being fed to the knife through a slot 15 for severance, after which it 10 is delivered to the purchaser through the delivery opening 7 or 8, as the case may be.

The respective vending units 10, 11, are provided with the usual coin-chutes 16, having conventional magnetic deflecting elements 17 (see 15 Figure 4) for attracting spurious metallic disks or tokens from operative relation to the vending mechanism. It is deemed unnecessary to enter into details of the vending mechanism other than to recite that the combined machine assembly 20 includes a continuously rotating power shaft 18 extending transversely of the machine and projecting with its opposite ends beyond the two side plates 19, 20, respectively of the supporting framework.

25 On this shaft 18 are cam elements 21, which rotate continuously therewith, one of said cam elements intermittently rocking a lever element 22 whose upper end portion is turned angularly to enter an opening in the coin-chute wall, as at 23 (see Figures 3 and 4), whereby to support the coin when first dropped into the chute and until the proper time for the release of the coin to effect the operation of the stamp-delivering mechanism, which operation is effected by the insertion 30 of the coin into the path of one of the cams of the elements grouped and generally designated by the numeral 21, and, through a system of levers 24, the knife element 15, which is normally yieldably held in retracted position, by a spring element 25, is operated, that is to say, the knife is swung upwardly on its pivot 26 by the action of the cam and lever mechanism, the stamp strip is fed the given distance, and, after the cam has moved beyond its effective position, 35 the spring element 25 retracts the knife with a snap-action and the purchased portion of the stamp strip is thereby severed and delivered through the delivery opening 7 or 8, as the case may be, and as hereinbefore set forth. It is understood 40 that the mechanism just described is duplicated on opposite sides of the machine in correlation to the respective vending units 10 and 11.

Fixed on the shaft 18, to rotate therewith between the left side plate 19 and the adjacent vending unit 10, is a relatively large gear wheel of the sprocket type, 27, which is belted to a relatively small wheel 28 on a transverse motor-driven counter-shaft 29, by a sprocket-chain 30. The 45 motor is preferably of an approved electrical type, indicated conventionally, as at 31 (see Figures 5 and 6), and the counter-shaft 29 is projected from a reduction gear housing 32, also shown conventionally in the drawings and obviously containing 50 an approved system of gearing whereby the counter-shaft 29 receives its power from the main shaft of the motor 31, at a reduced speed.

55 Preferably, the motor 31 is controlled through a suitable rheostat 33, having a dial 34, and an adjusting knob 35. One of the motor circuit wires 36, from the plugging-in socket 37 (see Figure 4) passes through this rheostat in the regular manner and, therefore, no further detailed illustration or description is deemed necessary to a full 60 understanding of the utility of the arrangement.

The advertising endless-belt strip or film, designated, generally, by the numeral 38, by dot-and-dash lines in Figures 5 and 6, and in full lines in Figures 3, 7 and 8, in which three latter figures of the drawings, the details of the particular preferred manner of detachably connecting the meeting end portions of the separate panel or sheet members 39 is illustrated. This strip or film may be made of any suitable transparent or translucent material. An ideal material is ordinary tracing cloth on which drawings are lined for purposes of reproduction by direct contact blue or other photo-printing processes. However, continuous strips or joined individual panels or sheets of material may be made of flexible cel- 10 15 loid or like characteristic substance.

As shown, the meeting marginal portions of the respective panels or sheets 39 are cut away, as at 40, to produce tongues 41, those at one end of the panel or sheet being staggered with relation 20 to those at the opposite end. The tongue portions 41 are looped, as at 42, and stitched or cemented at their ends to the base portions of the tongues or to the body of the sheet. In assembling the several panels or sheets 39 the looped tongue portions 25 are inserted in the openings of the meeting ends of the adjoining panel or sheet, and a wire element 43 is threaded through the aligned loops, thereby 30 detachably securing the panels or sheets 39 together with a hinge-like joint, by which provision, 35 not only is the requisite flexibility of the assembled strip maintained but the several panels or sheets are detachable and interchangeable.

Advertising matter is printed, painted or otherwise produced on the respective sheets or panels 39, and to illuminate the displayed advertisement a light bulb 44 (see Figure 5) is placed conveniently beneath the strip 38, within the supporting frame-work, and in the region of the window opening 9 of the cabinet or outer casing 1. This 40 light bulb may be uninterruptedly lighted, but, preferably, its electrical circuit is broken at intervals to cause a flashing of the light to attract attention. This is accomplished in any approved manner, but, for purposes of illustration, a circuit breaker 45 is provided, as shown conventionally in Figures 4 and 10 of the drawings. As shown, the device comprises a stationary terminal plate 46 and a co-operating spring tongue terminal element 47 set to be normally spaced and 50 insulated from the plate 46, as at 48, one of the circuit wires 49 from the plugging-in socket 37 being connected to the plate 46, while a continuation 55 of said wire 49 leads from the spring tongue element 47 to the lamp bulb in an obvious manner. The other circuit wire 51 for the lamp leads directly from the plugging-in socket 37 to the lamp.

Arranged in cooperative relation to the spring tongue terminal element 47 is a lever arm 52 having a cam projection 53 thereon which is slidably engaged by the peripheral portion of a disk 54, said peripheral portion, for the major part thereof, causing the lever arm 52 to be depressed, thereby pressing the spring tongue element 47 into 60 electrical contact with the stationary plate 46. However, when a notch 55 in the disk reaches the cam portion 53 of the lever arm 52, said arm is urged upwardly on its pivot by the spring tongue element 47 and electrical contact between the 65 tongue element and stationary plate 46 is broken, as shown in Figure 10, the break being, of course, only momentary and causing the light to blink.

The circuit breaker controlling disk 54 may be rotated by any suitable means, but, as shown, it 75

- rotates with a gear wheel 56 which meshes with a gear 57, which latter is in turn meshed with a pinion 58 on the constantly rotating power shaft 18 and being located at the outer side of the right plate 20 of the frame-work structure (see Figure 9). The gear 56 is conveniently mounted on a stud or stub-shaft 59 and the gear 57 on a similar supporting shaft 60, each protruding from the side plate 20.
10. The advertising endless-belt strip or film is carried about a multiplicity of rollers, two of which, as shown, namely 61 and 62, carrying the strip or film parallel with the inclined upper forward portion of the machine (see Figures 5 and 6). At the rear of the roller 62 is a roller 63. Rearward of and in a plane slightly below the roller 61, is a roller 64, over which the strip or film is carried substantially horizontally. Forward of and below the roller 64 is a roller 65, over which 15 the strip or film passes from a roller 66 of relatively large diameter. This roller 66 preferably has a peripheral portion 67 of hard rubber and it is relatively smooth surfaced. Rearward of and 20 closely adjacent to the roller 66 is a relatively small roller 68 which may be truly cylindrical throughout, but, in practice, is preferably concaved slightly from end to end, whereby to have a tendency to keep the strip or film centralized and thereby insure the true tracking of the strip 25 or film in its travel.

The several other rollers are arranged to carry the strip or film in looped and re-looped formation in order to have an extent of display surface compactly stored within the confines of the cabinet or outer casing.

Above the relatively small roller 68 is a roller 69, and above the latter is a group of three rollers 70, 71 and 72. Just below the rollers 62 and 63 are a horizontal series of closely arranged 30 rollers 73, 74, 75 and 76, as shown more clearly in Figure 6, while in the lower part of the frame-work, there are three closely arranged rollers 77, 78 and 79, and a slightly remote roller 80. A final roller 81 is removably mounted by having 35 its axial end bearing extensions 82 received in bayonet-slots 83 provided therefor in the lower, rear marginal portions of the side plates 19, 20, of the frame-work (see Figure 6).

Preferably, the upper roller 76 has its end 40 bearing extensions 84 located in vertical slots 85 in the side plates 19, 20, whereby the roller is guided vertically, said roller being yieldably suspended by tension springs 86 which are secured at their lower ends to clips 87 in which the end 45 bearing extensions of the roller are journalled, the upper ends of the springs 86 being attached to supporting studs 88. The springs 86 normally tend to pull the roller upwardly in the slots 85 and in so doing create a tension on the looped 50 strip or film, thereby keeping the latter taut on its rollers and also keeping the roller 81 with its end bearing extensions 82 seated in the vertical portions of the bayonet-slots 83. The yieldability of the roller 76, through the provision of the 55 springs 86, as aforesaid, also facilitates the removal of the roller 81, at will, to make adjustments of the strip or film 38 and for the interchange of the panels or sheets 39.

Normally, the relatively large roller 66 which 60 rotates constantly with the power shaft 18 on which it is fixed, slips circumferentially with respect to the strip or film 38 and while the strip or film is at its period of rest, during which time a brake element 89, comprising a transverse bar, 65 is pressing the adjacent portion of the strip or

film 38 on a transverse table or shelf 90 (see Figures 3, 5, 6 and 9), said table or shelf underlying the horizontal portion of the strip or film 38 which rides freely thereover when the brake is released and the strip or film is being caused to 5 travel a given distance to expose the next succeeding advertisement, or, in other words, the strip is intermittently moved step by step, the distance equal to the length of one individual panel or sheet member 39 and with relation to 10 the window or display opening 9 of the cabinet or casing 1.

The brake element 89 has a right angular downward extension 91, which is conveniently guided in any suitable manner, but, for purposes 15 of conventional illustration, its lower end portion is slidably fitted in a bracket or clip member 92 (see Figure 9), and it is normally urged downwardly by a tension spring 93, the horizontal body portion proper 89 of the brake element being located in rectangular slots 94 provided therefor in the side plates 19, 20, of the frame-work.

To effect the timed release of the brake element from contact with the strip or film 38, the 20 downward vertical extension 91 is preferably provided with a lateral stud 95 which is engaged by an arm of a lever member 96, said member having an upward end extension 97 which is 25 slidably engaged by a rotating cam disk 98 rotatable with the gear 57, hereinbefore described in connection with the operation of the circuit breaker for the lamp bulb 44. The ratio of the gear 57 and the pinion 58 is proportioned so that, during approximately one-half revolution of the 30 disk 98, the brake is applied and during the other half revolution the brake is released. The high or cam portion of the disk 98 is shown in Figure 35 9 of the drawings as just engaging the lever arm extension 97 and the brake is released as shown 40 in Figures 3, 5, 6 and 9.

As shown in Figure 9, the portion of the cam disk 98 which engages another lever member 99 to effect the feeding or travel of the strip or film 38, is just about to engage said lever member, it 45 being well to here note that the portion of the cam which co-operates with said second mentioned lever member 99 is a little shorter circumferentially than the portion thereof which co-operates with the lever member 96 first mentioned.

The lever member 99, at its forward end portion, engages a stud 99^a which is projected through an arcuate slot 100 in the side plate 20, said stud being carried by a yoke-like frame 101, 55 hingedly supported by trunnions 102 at each end, said trunnions being journalled in apertures provided therefor in the opposite side plates 19, 20. This yoke-like frame 101 has a presser-roller 103 journalled therein, said roller having a sponge-rubber peripheral portion 104 to contact with the large roller 66 hereinbefore described.

When the lever member 99 is actuated by the cam disk 98 to lift the stud 99^a, the yoke-like frame 101 is correspondingly lifted on its trunnions 102, and the soft surfaced, cellular material roller 103 is pressed tightly upon the portion of the strip or film 38 which is about the roller 66, and as the brake element 89 is at this time released from that portion of the strip or film lying over the table or shelf 90, the strip or film is consequently advanced one step to expose the next succeeding panel or sheet member 39 under the window opening 9. As soon as the movement of the strip or film is accomplished, the presser- 70 75

roller 103 is permitted to drop from engagement with the strip or film in the region of the roller 66 and the brake element is dropped by gravity and further urged downwardly by its spring element 93. Thus the operation of the strip or film 38 goes on intermittently, with the illuminating lamp intermittently blinking, and the stamp vending mechanism is partly operating continuously, but the stamp-delivering portion of the mechanism is only operated upon the insertion of the proper coin by the purchaser in the manner as hereinbefore described.

A machine as set forth herein in accordance with the present invention is operated and maintained economically, with a profit out of the revenue derived from the legitimate charge to the advertiser or advertisers utilizing the spaces provided by the respective panels or sheets 39 of the endless-belt strip or film 38, whereby postage stamps can be sold at face value, as an accommodation for patrons of stores or at stations in public places, whereas, by the use of an ordinary stamp vending machine, operated with no other source of revenue, the stamps are necessarily vended at a substantial premium to cover cost, at least, of manufacture and maintenance of the machine.

Obviously, the machine may be modified in details of structure and general arrangement, in many respects, without departing from the spirit and scope of the invention as defined by the appended claims. The invention, therefore, is not limited to the specific construction and arrangement shown in the accompanying illustrative drawings.

What is claimed is:

1. A machine of the character described, comprising a cabinet having a display window, an endless-belt strip on which advertising matter is placed in sequential panel arrangement and movable in registerable relation to said display window, a common power element operating continuously, means for intermittently connecting said power element with said advertising endless-belt strip whereby to successively bring the respective panels thereof into register with the display window of the cabinet, said means comprising a smooth surfaced roller about which said endless-belt strip passes and the roller normally rotating as a part of the power element and slipping with respect to the strip, and a presser roller movable intermittently to press said endless-belt strip upon said rotating roller whereby to cause intermittent travel of said strip, said presser roller having a sponge rubber circumferential portion.

2. In a machine of the character described, an endless-belt advertising strip, a series of supporting rolls about which said strip travels in windingly looped arrangement, resilient means

for holding said strip in tautened condition, a continuously rotating feeder-roll having a relatively hard and smooth peripheral surface, and about which said strip travels, brake means including a supporting table-like element over which the strip travels and a brake-bar extending transversely of the strip, thereabove, and in co-operative relation to said table-like supporting element, automatically operating spring tensioned means for normally holding said brake-bar in clamping relation to that portion of said strip which is upon said table-like supporting element, means for periodically raising said brake-bar from such clamping relation, and means for effecting the travel of said strip while said brake-bar is so released, said last named means including a swingably supported yoke-like element, a presser-roll rotatably mounted in said yoke-like element, said presser-roll having a circumferential portion of material of the character of sponge-rubber, and means, operable after the release of said brake-bar and before said brake-bar is again applied in braking relation to the strip, whereby to actuate said yoke-like element to press said presser-roll in contact with that portion of said strip which is about said feeder-roll, said strip being thereby moved intermittently to successively display sequentially arranged advertising matter provided thereon.

3. A machine of the character described comprising a cabinet having a display window, an endless-belt strip on which advertising matter is placed in sequential panel arrangement, and movable in registerable relation to said display window, brake means including a supporting table-like element over which the strip travels and a brake-bar extending transversely of the strip, thereabove, and in co-operative relation to said table-like supporting element, and automatically operating spring tension means for normally holding said brake-bar in clamping relation to that portion of said strip which is upon said table-like supporting element, means for periodically raising the brake-bar from clamping relation, and a power element operating continuously, means for intermittently connecting said power element with said advertising endless-belt strip whereby to successively bring the respective panels thereof into register with the display window, the said power means comprising a smooth surfaced roller about which said endless-belt strip passes and the roller normally rotating as a part of the element and a presser roller movable intermittently to press said endless-belt strip upon said rotating roller whereby to cause intermittent travel of said strip at the times that the brake-bar is raised from clamping relation to that portion of said strip which is upon said table-like supporting element.

CLARENCE M. WHEELER. 60
